CLAIM

The ornamental design for an electrical box bracket, substantially as shown and described.

DESCRIPTION

FIG. 1 is a front view of my design for an electrical box bracket with the box portion shown in phantom.

FIG. 2 is a right side view of the electrical box bracket of FIG. 1.

FIG. 3 is a rear view of the electrical box bracket of FIG. 1.

FIG. 4 is a top plan view of the electrical box bracket of FIG. 1.

FIG. 5 is a bottom plan view of the electrical box bracket of FIG. 1.

FIG. 6 is a left side view of the electrical box bracket of FIG. 1.

FIG. 7 is a top perspective view of the electrical box bracket of FIG. 1.

FIG. 8 is another top perspective view of the electrical box bracket of FIG. 1; and,

FIG. 9 is a bottom perspective view of the electrical box bracket of FIG. 1.

The broken line showing is included for the purpose of illustrating environment and forms no part of the claimed design.
